UNITED STATES PATENT OFFICE.

WILLIAM HARTMANN, JR., OF ALBANY, NEW YORK.

FIRE-ESCAPE.

993,368.

Specification of Letters Patent. Patented May 30, 1911.

Application filed July 19, 1909. Serial No. 508,304.

To all whom it may concern:

Be it known that I, WILLIAM HARTMANN, Jr., a citizen of the United States, residing at the city of Albany, in the county of Albany and State of New York, have invented 5 certain new and useful Improvements in Fire-Escapes, of which the following is a specification.

My invention relates to fire escapes, and 10 the object of my invention is to provide a fire escape apparatus which may be quickly placed in position, and, when out of use, may be easily moved out of the way, together with such other elements and combinations 15 as are hereinafter more particularly set forth and claimed. I attain this object by means of the mechanism illustrated in the accompanying drawing, in which the figure is a longitudinal section showing an elevation 20 of parts of the apparatus.

In the sides of the box, A, is mounted a shaft, B. The drum, C, partly surrounds the shaft, B, but has an opening, D, therethrough allowing for the cable, E, to pass 25 through and be attached to the shaft B. The cable E is a part of the rope ladder, F, which is constructed of rope or wires, provided with rungs, f, at frequent intervals, with the center cable, E, constructed of 30 metal. There are thus, preferably, three cables, two on each side and one in the center. The rungs, f, extending across from one side to the other, engaging the central cable as 35 well. The ladder is wound about the drum, C, with the center cable, E, as hereinbefore stated, elongated and secured to the shaft B.

At each end of the shaft B, but within the box, A, I place a disk, G, having a serrated edge, g. Pivoted to the side of the 40 box, A, preferably above the disk, K, is a lever, H, carrying a dog, J, meshing with the serrations, g, in the disk G. The end of the lever, H, also carries a dog K. The lever, H, and dogs J and K are used for winding 45 up the ladder on the drum C. Each of the disks, G, is provided with an annular flange, L, on one side, with which the strap M engages. The strap, M, being secured by means of the spring N to the bottom of the box A. 50 The resiliency of the spring N causing the

strap M to be held tightly in contact with the flange L and act as a brake.

For the purpose of releasing the brake-strap I attach a cable, P, to the spring, N, which passes over a sheave, p, in contact 55 with a sheave R, secured to the lever S. When the lever, S, is operated it will release the pull of the spring N on the strap, M, and therefore the flange L from contact with the spring. I connect a dog, T, with lever, S, 60 and place a rack, U, on the box, A, with which the dog T engages to hold the spring N distended after the lever S has been operated upon.

To one end of front of the box A I pivot 65 an arm, V, which may have an extension arm, W, telescoping therein. The extension arm, W, carries a disk, X, upon the periphery of which I preferably arrange a series of rollers, t, with which one of the cables forming the ladder, F, engages. I attach to the front of the box, A, a similar arm, V, and telescoping arm W and disk, X, with which the other cables of the ladder F engage.

For the purpose of keeping the ladder 75 from coming in too close contact with the wall of the house when the fire escape is in position I place a series of disks, Z, on the rungs, f, which will prevent the ladder from coming close to the wall of the building. On 80 the extension arm, W, I place the adjusting block, w, which may rest on the window sill, s, for the purpose of holding the disk, Z, in proper position out of the window or other opening.

A handle bar 2 is pivoted to the front of the box A and may act as a measure to show the distance that the box A should stand from the wall when in use. The box A is usually mounted upon casters or rollers, 3, 3. 90 When not in use, by means of a pulley, 4, and chain, 5, I may pull the arm, V, and telescoping arm, W, up out of the way.

What I claim as my invention and desire to secure by Letters Patent is:

In a fire escape, the combination with a box or casing, of a reel mounted therein, a flexible ladder carried by said reel, telescoping arms pivoted to the front of said casing near the bottom thereof, wheels or disks 100

2
mounted on the ends of the outer sections of said arms over which the ladder runs, a block adjustably mounted on said outer sections and adapted to engage the window sill or other support, said arms being adjustable for sills of different heights and for walls of different thickness.

In testimony whereof I have affixed my signature in presence of two witnesses.

WILLIAM HARTMANN, JR.
